(57) **CLAIM**

The ornamental design for a ceiling light, as shown and described.

DESCRIPTION

FIG. 1 is a front elevation view of a ceiling light, showing the design;

FIG. 2 is an enlarged front-bottom-right side perspective view of a middle reflector portion of the ceiling light of FIG. 1, showing the design.

FIG. 3 is an enlarged front-top-left side perspective view of the middle reflector portion shown in FIG. 2 of the ceiling light of FIG. 1, showing the design; and,

FIG. 4 is an enlarged front elevation view of the left reflector portion of the ceiling light of FIG. 1, which is the same as an enlarged rear elevation view of the right reflector portion of the ceiling light of FIG. 1, showing the design.

1 Claim, 4 Drawing Sheets
